ELECTRIC SWITCH

Gustav A. Lennholm, Des Moines, Iowa, assignor
to Square D Company, Detroit, Mich., a cor-
poration of Michigan

Application October 23, 1940, Serial No. 362,389

10 Claims. (Cl. 200—67)

This invention relates to electric switches and more particularly to an improved form of electric switch operating with a snap action.

One object of the present invention is to provide an improved form of electric switch having an economy and simplicity of construction.

Another object of the present invention is to provide an improved form of electric switch having provision for breaking a contact weld and restoring the switch to normal operation.

Another object of the present invention is to provide an improved form of electric switch in which the contacts are so moved as to provide a substantial "wiping" action before moving to disengaged position.

Another object of the present invention is to provide an improved snap acting electric switch in which a substantial contact pressure is maintained until the instant the contacts are quickly snapped to disengaged position.

Other objects and features of this invention will be readily apparent to those skilled in the art from the following specification and appended drawing illustrating certain preferred embodiments of the invention in which:

Figure 1 is a front elevational view of the electric switch according to the present invention with the cover partially broken away and showing the contacts in their engaged position.

Figure 2 is also a front elevational view of the electric switch, but with the contacts shown in their disengaged position.

Figure 3 is a sectional view on the line III—III of Figure 1.

Figure 4 is a sectional view on the line IV—IV of Figure 2.

Figure 5 is a sectional view on the line V—V of Figure 1.

Figure 6 is a sectional view on the line VI—VI of Figure 2.

The switch of the present invention is adapted for actuation both manually, and automatically in response to an external force. The embodiment as illustrated can be used in connection with a float for sump operations. Reversing of the switch top for bottom enables its use for tank operations.

The electric switch, according to the present invention, comprises an enclosure 1 having a removable front cover 2, adapted to be secured thereto. Two winglike portions 3 and 4 having openings therethrough for the passage of studs are provided upon the enclosure for the ready attachment of the switch at the desired operating point. Ledges 5 and 6 are provided within the en-

closure 1 at one end thereof and on these ledges are secured conducting members 7 and 11 by means of studs 8 and 12, the member 11 being further secured to the back wall 13 of the enclosure as by a stud 14. Studs 15 and 16 are threaded into the conducting members 7 and 11 and serve as means for securing circuit wires thereto. The ends of the conducting members 7 and 11 are inwardly bent as at 17 and 18, the outer surfaces of these ends lying in the same general plane and constituting the spaced stationary contacts for the switch.

A supporting member 19 of general double U-shape is secured to the base of the enclosure 1, 15 as by studs, and is insulated from the conducting members 7 and 11 by an upstanding wall portion 21. A generally U-shaped lever or supporting member 22 is pivotally mounted upon the supporting member 19, the legs of the lever 22 pivoting 20 within seats provided by the legs 23 and 24 of the supporting member 19. A contact carrying or switching member 25 formed of an insulating plate 26 and a metallic member 27 has an opening 28 therein through which projects a narrowed extension 29 of the lever 22 with the shoulder portions 31 on the lever 22 affording a support for insulating plate 26. A movable contact 32 is loosely supported on the plate 26 at one end thereof and serves to bridge the stationary contacts 17 and 18 to complete the circuit there-through. A depending tongue 33 bent from the metallic member 27 extends through opening 28 and provides a point of attachment for one end of an operating spring 35. The tongue 33 is bent 25 upwardly at its end 36 where the operating spring is attached and extends through the legs 37 and 38 of the lever member 19 when the contacts are in engaged position. This thus places the point of attachment of the end of the spring 35 above the plane of the upper face of lever member 22 as viewed in Figure 1 for a purpose to be hereinafter described. The opposite end of the spring 35 is secured to a generally U-shaped operator 41. The operator is pivotally mounted upon the supporting member 19, with its legs disposed outside the supporting member but having projections thereon cooperating with seats provided in the legs 42 and 43 of the supporting member. The spring 35 serves to definitely bias both the lever 22 and the operator 41 firmly within their respective seats on the supporting member. The extent of pivotal movement of the operating member 41 is defined by the oppositely disposed surfaces 45 and 46 on the legs 23 and 25 of the supporting member. An inwardly directed flange 47 carried by a leg of

the operating member 41 is adapted to positively engage the lever member 22 to initiate the movement of the parts from the engaged to the disengaged position. This flange, through its ability to positively engage the lever member 22, thereby also serves to force the contacts apart to break any weld which might occur between the contact surfaces. A terminal junction plate 48 is secured to the back of the base 13 of the enclosure 1 by a stud 49 and carries the studs 51 and 52 to serve as means for connecting circuit wires thereto, this junction plate being insulated from the other switch parts.

In the operation of the device from the "on" position shown in Figure 1 to the "off" position shown in Figure 2, the operator 41 moves in a clockwise direction to first bring the flange 47 into engagement with the lever member 22 thereby initiating the movement of the lever member 22 and of the switching member 25 carried thereon. Movement of the operator moves the operating spring 35 and this tends to move the contact carrier generally vertically, as shown, the lever 22 pivoting about its mounting or supporting member 19. The movements of both the operator 41 and the lever 22 continue thus until spring 35 is carried through the pivots of lever 22 whereupon the lever quickly snaps to its full open position of Figure 2. The lever 22 is limited in its opposite movements by the engaging of insulating plate 26 with top and bottom walls of the enclosure. It is to be noted that the attaching of the end of operating spring 35 to the portion 36 of the tongue 33 to place the point of attachment above the plane of the upper surface of lever member 22 and above the horizontal plane through the point of engagement of carrier 25 and lever member 22 when the contacts are engaged will cause the force of the spring 35 to act upon the contact carrier 25 to urge it in a clockwise direction about its abutting engagement with the shoulders 31 of the lever member 22. The carrier is prevented from moving in this direction through the engagement of the movable contact 32 with the stationary contacts 17 and 18 so that the force of the spring 35 urging the clockwise movement of the carrier 25 causes the movable contact 32 to press tightly against the stationary contacts 17 and 18 thereby providing a very definite contact pressure. This definite contact pressure is maintained while the contact carrier 25 and the movable contact 32 are being moved in a generally vertical direction and until the spring 35 is carried through the pivot point of the lever 22 to thereby shift the direction of the force of the spring 35 to quickly move said lever 22, the contact carrier 25 and the movable contact 32 thereon in a counterclockwise direction.

In the movement of the operating member 41 from the "off" to the "on" position, spring 35 is carried in the reverse direction through the pivots of lever 22 whereupon the carrier 25, contact 32 and lever 22 will be quickly snapped in clockwise direction to the contacts engaged position of Figure 1. In this movement, prior to the snapping action, the carrier 25 will rotate counterclockwise about the shoulders 31 so that proper engagement of contact 32 with the stationary contacts is assured and the possibility of accidental edge contact is prevented. An additional feature of the switch is the relatively large wiping action of the contacts which is secured. In the movement from "on" to "off," the movable contact will slide for a very appreciable distance

on the stationary contact surfaces while contact pressure is positively maintained. This movement continues either through positive engagement of flange 47 or through the bias of spring 35 until the instant the spring passes through the pivots of lever 22, whereupon the contacts quickly snap open. This contact wipe is a very desirable feature for reliable operation and, coupled with the positive force from flange 47, results in an extremely reliable and efficient switch, although relatively few and inexpensive parts are used.

The switch operator 41 may be manipulated manually or by any exterior means, but the switch has shown itself especially adapted for operation by a float in response to changes in liquid level, such as used in the control of sump pump motors and similar liquid level regulators.

While certain preferred embodiments of the invention have been specifically disclosed, it is understood that the invention is not limited thereto and is to be given its broadest possible interpretation within the terms of the following claims.

What is claimed is:

1. In an electric switch, a stationary contact, a movable contact, a switching member movable to move said movable contact into and out of engagement with said stationary contact, a fixed supporting member, an element pivotally supporting said switching member and itself pivotally mounted on said fixed supporting member, an overcenter spring means secured to said switching member, means operative to displace the point of attachment of said overcenter spring to the switching member from one side to the other of the pivotal supporting element to urge a rotative movement of said switching member relative to said pivotal supporting element before said switching member and said pivotal supporting element are snapped to a second position.

2. In an electric switch, a stationary contact, a movable contact, a switching member movable to move said movable contact to engaged and disengaged positions, a fixed supporting member, a generally U-shaped member supporting said switching member and being pivotally mounted on the fixed supporting member, an overcenter spring means secured to said switching member, means operative to move said overcenter spring means to wholly displace the line of action thereof from one side of said U-shaped member to the other side thereof to effect a pivotal movement of said U-shaped member while said U-shaped member is moving between contacts engaged and disengaged positions, said means including a pivotally mounted operating lever having the legs thereof disposed outside of said generally U-shaped member.

3. In an electric switch, a stationary contact, a movable contact, a switching member movable to move said movable contact into and out of engagement with said stationary contacts, a fixed supporting member, a movable supporting member for said switching member pivoted on said fixed supporting member, an overcenter spring means secured to said switching member, said spring means exerting its bias to maintain said movable supporting member in position upon said fixed supporting member, means to move said spring means to effect pivotal movement of said movable supporting member and a generally rectilinear movement of said movable contact face across said stationary contact face before said

spring means passes through the pivot of said movable supporting member, movement of the spring means through said pivot effecting snap movement of said movable supporting member and said switching member from an engaged to a disengaged position.

4. In an electric switch, a stationary contact, a movable contact, a switching member movable to move said movable contact into and out of engagement with said stationary contact, a fixed supporting member, a generally U-shaped member supporting said switching member and being pivotally mounted on the fixed supporting member, and overcenter spring means secured to said switching member, means operable to move said spring means to effect pivotal movement of said movable supporting member and a generally rectilinear movement of the movable contact face across the stationary contact face before said spring means passes through the pivot of the movable supporting member, movement of the spring means through said pivot effecting snap movement of said movable supporting member and said switching member from an engaged to a disengaged position, said means including a pivotally mounted generally U-shaped operating member having the legs thereof disposed outside of said generally U-shaped supporting member.

5. In an electric switch, a stationary contact, a movable contact, a switching member movable to move said movable contact into engaged and disengaged positions, a pivotal member supporting said switching member and having an opening provided therein, a projection on said switching member extending through said opening when the contacts are in engaged position and moving out of said opening when said movable contact is moved to disengaged position, means to move said pivotal member and to urge rotative movement of said switching member about its support while said pivotal member is in motion to maintain substantial contact pressure between said stationary and movable contacts until the instant of disengagement, said means including an operating member and spring means interconnecting said operating member and said projection on said switching member.

6. In an electric switch, a stationary contact, a movable contact, a switching member movable to move said movable contact into engaged and disengaged position, a pivotal member supporting said switching member and having an opening provided therein, means carried by said switching member and oscillatably movable through said opening from one side to the other of said pivotal member, means operative to move said pivotal member and to urge rotative movement of said switching member about its support while said pivotal member is moving to maintain substantial contact pressure between said stationary and movable contacts until the instant of disengagement, said means including an operating member and spring means interconnecting said operating member and said oscillatable means.

7. In an electric switch, a stationary contact, a movable contact, a switching member carrying said movable contact for cooperation with said stationary contact, a pivotal member supporting said switching member and having an opening therethrough, a projection on said switching member extending through said opening means to oscillatably move said projection through said opening from one side of said piv-

5 otal member to the other to effect first a rotative movement of said switching member about its engagement with the pivotal member and then to effect a snap movement of said switching member and said pivotal member, said means including an overcenter spring secured to said projection and an operating member for actuating said overcenter spring.

8. In an electric switch, a stationary contact, a pivotal lever, a contact carrier supported intermediate its ends upon said pivotal lever and at substantially right angles thereto, said contact carrier having a contact surface disposed thereon adjacent one end thereof for cooperation with 10 said stationary contacts to make and break an electrical circuit therethrough, a projecting member provided on said contact carrier at the opposite end thereof, a pivotal operating member, a spring interconnecting said operating member and said projecting member, an extension on said operating member for movement thereof, to move the point of attachment of the spring to the projecting member from one side to the other of the point of support of said contact carrier on said pivotal supporting member to move said pivotal supporting member and to urge rotative movement of said contact carrier about its support while said pivotal member is in motion to maintain substantial contact pressure between the contacts until said spring means snaps said contact carrier to "off" position.

30 9. In an electric switch, a stationary contact, a first pivotal lever, a second pivotal lever, each of said pivotal levers being movable from one side of the other lever's pivot to the other, a contact carrier supported intermediate its ends upon said first pivotal lever, a contact surface disposed upon said contact carrier adapted to cooperate with said stationary contact, a projection upon said contact carrier, and extending from the same side of said contact carrier as said contact surface is disposed, a spring means interconnecting said projection and said second pivotal lever, an extension on said second pivotal lever whereby said lever may be moved to move the line of force of said spring means from one side to the other of the plane containing the pivots of said levers to move said projection and actuate said first pivotal member and urge rotative movement of said switching member about its support while said first pivotal member is moving to maintain substantial contact pressure between said stationary and movable contacts until the instant of disengagement.

50 10. In an electric switch, a stationary contact, a support, a pair of oppositely extending pivotal levers mounted thereon, the pivotal axis for each lever being located on said support intermediate the ends of the other lever, a contact carrier having a contact surface thereon for cooperation with said stationary contacts and supported upon one of said pivotal levers at substantially right angles thereto, a projecting member on said contact carrier, a spring means interconnecting said projecting member and the second of said pivotal levers, an extension on said second pivotal lever for effecting movement thereof to actuate said spring means to move said projecting portion from one side of a plane containing said pivotal axes to the other to actuate said first pivotal member and to urge rotative movement of said switching member about its support while said pivotal member is in motion.
